UNITED STATES PATENT OFFICE

137,453

DESIGN FOR A PORTABLE SANDING MACHINE

William Allan Lintern, Berea, Ohio, assignor to
The Lintern Corporation, Berea, Ohio, a cor-
poration of Ohio

Application August 2, 1943, Serial No. 110,822

Term of patent 7 years

To all whom it may concern:

Be it known that I, William Allan Lintern, a citizen of the United States, residing at Berea, in the county of Cuyahoga and State of Ohio, have invented a new, original, and ornamental Design for a Portable Sanding Machine, of which the following is a specification, reference being had to the accompanying drawing, forming a part thereof.

Fig. 1 is a perspective view showing the right hand side of a sanding machine illustrating my new design; and

Fig. 2 is a similar view showing the left hand side.

The salient features of the design for the portable sanding machine disclosed reside in the handle and body casing portions.

I claim:

The ornamental design for a portable sanding machine, substantially as shown and described.

WILLIAM ALLAN LINTERN.
